LOOM HARNESS

John Jacob Kaufmann, Elkins Park, Pa., assignor
to Steel Heddle Manufacturing Company,
Philadelphia, Pa., a corporation of Pennsyl-
vania

Application December 5, 1944, Serial No. 566,655

8 Claims. (Cl. 139—92)

This invention relates to loom harness, and it relates more particularly to that type of harness, a form of which is shown and described in my previous Letters Patent No. 2,047,511, dated July 14, 1936. Such loom harness, while being of general application, is particularly useful in those installations where it is desired to insert the warp ends through the heddles by means of the automatic warp drawing-in machines which are now in more or less common use.

As was pointed out in my previous Letters Patent above referred to, when it is desired to employ warp drawing-in mechanism for automatically entering the warp, it is essential that the heddles be permitted entire freedom of movement upon their supporting rods, without being obstructed in any way by the devices which are commonly used in loom harness frames of the ordinary type for the purpose of supporting the heddle rods intermediate their ends.

While the loom harness frames of the type shown and described in my previous Letters Patent have proved reasonably satisfactory, nevertheless, some difficulty has arisen by reason of careless handling of the frames by the operators and the C-shaped rods employed for supporting the heddles would become deformed in use, thereby rendering it difficult to release the heddle supporting rods from the intermediate supporting devices whenever it became necessary to remove the rods from the frame.

While my previous Letters Patent contained a suggestion, shown in Fig. 8 of the drawings of said patent, that the heddle supporting rods might be made of flat bar stock, nevertheless, this construction did not prove entirely satisfactory as no practical means for securing such heddle rods to the top and bottom rails of the heddle frame has heretofore been devised.

The principal object of the present invention is to provide heddle frames, of the character aforesaid, in which the rods for supporting the heddles are made of flat bar stock, and which are so supported with respect to the top and bottom rails of the respective heddle frames as to be quickly and easily detached therefrom whenever it is desired to dismantle the frame for any purpose.

The nature and characteristic features of the present invention will be more readily understood from the following description, taken in connection with the accompanying drawings, forming part hereof, in which:

Figure 1 is a front elevation of a loom harness frame embodying the main features of the pres.

ent invention, the same being shown with heddles mounted thereon which are adapted for use in connection with an automatic warp drawing-in machine;

5 Fig. 2 is a vertical section, enlarged, taken approximately on the line 2—2 of Fig. 1;

Fig. 3 is a horizontal section, also enlarged, taken approximately on the line 3—3 of Fig. 1;

10 Fig. 4 is a fragmentary detail, enlarged, of a portion of a heddle frame illustrating a modified form of the invention;

Fig. 5 is a vertical section taken approximately on the line 5—5 of Fig. 4; and

15 Fig. 6 is a horizontal section taken approximately on the line 6—6 of Fig. 4.

It should of course be understood that the description and drawings herein are illustrative merely, and that various modifications and changes may be made in the structure disclosed 20 without departing from the spirit of the invention.

Referring now more particularly to Figs. 1, 2, and 3 of the drawings, the heddle frame proper may be of any preferred construction. For example, as shown, the same may comprise top and bottom rails 10 connected at their ends by end struts 11. The heddle supporting rods 12 in this instance are made of strips of flat bar metal extending from end to end of the frame, and each having its end portions extending through slots in the end struts 11 of the frame in the usual and customary manner. Each of the projecting end portions of each heddle rod is also provided with the usual aperture 15, which is engaged by 25 the hooked end of a spring retaining member 16 mounted in the end struts 11 of the frame.

It will of course be understood that various other forms of retaining means at the ends of the heddle rods 12 may be used if desired, although 30 it has been found that spring members of the character shown are quite satisfactory for the purpose.

Referring now more particularly to Figs. 1, 2, and 3 of the drawings there is therein shown a 35 preferred form of device for supporting the heddle rods 12 intermediate their ends. As there shown, the heddle rods 12 are provided, at each of the places where a supporting device is disposed, with a plate member 17 which is secured 40 to the heddle rod by means of rivets 18, and a spacing member 19 is interposed between the heddle rod 12 and the plate member 17 for a 45 purpose to be presently explained.

The plate member 17 extends toward the rail 50 of the frame from which the heddle rod is sup-

ported, and said plate member 17 is provided near the edge thereof with a longitudinal slot 20. The portion of the plate member 17 which is disposed between the slot 20 and the outermost margin of the plate member 17 is disposed in a milled groove 21 on one side of the enlarged head portion 22 of a bolt member 23 which extends through the rail 10 of the frame.

The plate member 17 is also provided with a tongue portion 24 which extends from one of the end margins of the plate member 17, and is bent around and positioned in another groove 25 milled in the head portion 22 of the bolt member 23.

The bolt member 23 is provided at its outer end with a threaded portion 26, and this threaded portion is engaged by a complementally threaded sleeve 27. The sleeve 27 is provided with a flange 28 (see Fig. 4) on its inner end, and said flange 28 is confined between a washer 29, seated in a recess 30 in the rail, and a plate member 31 which is secured in the rail by means of screws 32.

The sleeve 27, mounted on the threaded end 26 of the bolt permits an adjustment of the bolt 23 in the frame to maintain the heddle supporting rods 12 in the frame at the proper distances apart. The screws 32 are tightened, after the adjustment is made, to maintain the bolt 23 in each instance in the proper adjusted positions.

The heddles 35 employed may be substantially the same as those shown in Figs. 2 and 3 of my Letters Patent No. 2,047,511, being preferably made from thin flat strips of metal of a width corresponding to the widest portion of the heddle. The central portion 36 of each heddle 35 is preferably left the full width of the strip, as is also each end portion 37 thereof, but the parts 38 of the heddle 35 between the central portion 36 and the respective end portions 37 are preferably cut down to a considerably narrower width to reduce the weight of the installation, and to permit each heddle 35 to be turned as required for the functioning of the warp drawing-in machine.

The central portion 36 of the heddle 35 is provided with the usual punched and formed warp eye 39, the shanks of which may, if desired, be formed in bowed conformation out of the main plane of the heddle proper.

The central portion 36 of the heddle 35 is left the full width of the strip, for a greater length than would be required merely for the warp eye 39, to permit the punching adjacent the warp eye 39, of a key hole slot 40, which is provided for installations in which the warp is entered by means of a warp drawing-in machine.

Each of the end portions 37 of each of the heddles 35 shown in Figs. 2 and 5 of the drawings, which, as hereinbefore mentioned, is left the full width of the strip from which the heddle is formed, is punched out to provide a slot 41 for mounting the heddles on the rods 12 and one side portion thereof is cut away as at 42 substantially midway the extension of the slot 41, so that when the heddles 35 are slid sidewise on the rods 12, they will pass freely without being obstructed by the spacing member 19 which are disposed between the heddle rods 12 and the plate members 17 each forming part of a supporting device for the rods intermediate the ends.

By this arrangement there is provided at each end portion 37 of each heddle 35, a solid strip 43 which extends over one face of the heddle

rod 12 and fingers 44 on the other side of said heddle rod 12 which engage the other face of said rod.

The slot 41 provided at each end of each heddle 35 is of a length greater than the width of the heddle rod 12 to permit the heddles 35 to have the usual and necessary slight up and down movement on the heddle rods, so that the heddles 35 may readily accommodate themselves to the slightly varying positions of the warp ends controlled thereby. The width of the opening 41 in the side of each end portion 37 of each heddle 35 is such that in the uppermost and lowermost positions of the heddles 35 on the rods 12 the fingers 44 will clear the spacing members 19 disposed between the heddle rods 12 and the supporting plate members 17.

The form of the invention shown in Figs. 4, 5, and 6 of the drawings, is substantially the same as the form hereinbefore described, with the single exception that the bolt head, instead of being enlarged and having milled out grooves, is made as illustrated in Fig. 5. As there shown the head portion 22a of the bolt member 22a is flattened and has its end bent around at right angles as at 45 to extend within the slot 20 of the plate member 17. In this instance the plate member is also provided with the bent around tongue portion 24 which serves to prevent the portion 45 of the head of the bolt, which extends at right angles, from becoming disengaged from the slot 20 in the plate member 17 in the normal arrangement of the various parts.

In either of the forms it will be noted that the bent around tongue 24 of the plate member 17 terminates at such point as to permit the head of the bolt, in either form, to be disengaged from the slot 20 of the plate member 17, when the heddle supporting rod 12 has its end portions disengaged from the retaining hooks and is slid endwise a sufficient distance, first to permit the plate members 17 carried by said heddle rod 12 to become disengaged from the head portions of the bolts, and thereafter to become disengaged from the end struts 11 of the frame in which they are mounted.

It will be seen that by the foregoing arrangement there is provided a simple and efficient means for supporting the heddle rods intermediate their ends, which is so constructed and arranged as to permit the heddles to pass freely from one end to the other of the heddle rods without interference from the supporting means.

I claim:

1. In a loom harness including a heddle frame having top and bottom rails and heddle supporting rods comprising thin flat metallic strips removably mounted in said frame, the means for supporting said rods intermediate the ends thereof comprising, in each location, a plate member secured to the rod in spaced relationship, and a separate bolt member mounted in one of the rails of the frame; said plate member and bolt member being in locked engagement with each other; and means carried by one of said members for normally maintaining the locked engagement of said parts.

2. In loom harness including a heddle frame having top and bottom rails and heddle supporting rods comprising thin flat metallic strips removably mounted in said frame, the means for supporting said rods intermediate the ends thereof comprising in each location, a plate member secured to the rod in spaced relationship, and a separate bolt member mounted in one of the rails

of the frame; said plate member and bolt member being in locked engagement with each other; and a tongue member carried by one of said parts for normally maintaining the engagement of said parts.

3. In loom harness including a heddle frame having top and bottom rails and heddle supporting rods comprising thin flat metallic strips removably mounted in said frame, the means for supporting said rods intermediate the ends thereof comprising, in each location, a plate member secured to the rod in spaced relationship, and a separate bolt member mounted in one of the rails of the frame; said plate member having a slot extending parallel to the rod, and the bolt member having a head portion engaging the plate member and provided with a part extending into the slot in the plate member, and means for normally maintaining the engagement of said head portion of the bolt with the plate member.

4. In loom harness including a heddle frame having top and bottom rails and heddle supporting rods comprising thin flat metallic strips removably mounted in said frame, the means for supporting said rods intermediate the ends thereof, comprising, in each location, a plate member secured to the rod in spaced relationship, and a separate bolt member mounted in one of the rails of the frame; said plate member having a slot extending parallel to the rod, and the bolt member having a head portion engaging the plate member and provided with a part extending into the slot in the plate member; and a tongue member extending from a portion of the plate member in engagement with a part of the head portion of the bolt for normally maintaining the engagement of said head portion of the bolt with the plate member.

5. In loom harness including a heddle frame having top and bottom rails and heddle supporting rods comprising thin flat metallic strips removably mounted in said frame, the means for supporting said rods intermediate the ends thereof comprising, in each location, a plate member secured to the rod in spaced relationship, and a separate bolt member mounted in one of the rails of the frame; said plate member having a slot extending parallel to the rod, and the bolt member having a head portion engaging the plate member and provided with a part extending into

5 the slot in the plate member; and a tongue member extending from one end of the plate member in engagement with a part of the head portion of the bolt for normally maintaining the engagement of said head portion of the bolt with the plate member.

6. In loom harness including a heddle frame having top and bottom rails and heddle supporting rods comprising thin flat metallic strips mounted in said frame and being removable therefrom by sliding lengthwise, the means for supporting said rods intermediate the ends thereof comprising, in each location, a member carried by the rod, and a separate bolt member mounted in one of the rails of the frame; said members being normally in locked engagement with each other but being separable upon sliding the rod lengthwise.

7. In loom harness including a heddle frame having top and bottom rails and heddle supporting rods comprising thin flat metallic strips mounted in said frame and being removable therefrom by sliding lengthwise, the means for supporting said rods intermediate the ends thereof comprising, in each location, a member carried by the rod, and a separate bolt member mounted in one of the rails of the frame; said members being normally in locked engagement with each other but being separable upon sliding the rod lengthwise, and means for maintaining the locked engagement of said members when the same are in their normal relative positions.

8. In loom harness including a heddle frame having top and bottom rails and heddle supporting rods comprising thin flat metallic strips mounted in said frame and being removable therefrom by sliding lengthwise, the means for supporting said rods intermediate the ends thereof comprising, in each location, a member secured to the rod, and a separate bolt member mounted in one of the rails of the frame; one of said members being slotted and the other of said members having a portion engaging the slot to secure said members to each other, said members being separable upon sliding the rod lengthwise, and means for normally maintaining the locked engagement of said members.
